UNITED STATES PATENT OFFICE.

WILLIAM DIETER, OF NEWARK, NEW JERSEY.

HYDROSTATIC MINE.

Application filed February 3, 1926. Serial No. 85,846.

This invention relates to submarine mines in the nature of depth bombs, such as are adapted to be dropped overboard from a ship or dropped from an aeroplane, and which sink in the water until they reach a predetermined depth, whereupon they explode. Such mines commonly include a main charge of high explosive which fills the greater part of the capacity of the shell or casing, a detonator usually in the form of a cartridge having the usual cap containing fulminate, and an intermediate explosive charge which is sometimes called the primer, and sometimes the booster charge. A spring-pressed diaphragm or other form of hydrostat is provided which moves under hydrostatic pressure as the mine descends, until the set depth is reached, whereupon a sear or other trigger device releases a hammer or firing needle which is projected by its weight or a spring, or by fluid pressure, and strikes the cartridge cap, exploding the cartridge, which in turn explodes the intermediate charge, and this in turn explodes the main charge.

Various provisions have been made for safeguarding against the premature explosion of such mines or bombs. One such means is to provide two hydrostatic diaphragms or pistons, the one set to a primary depth and the other to the secondary or final explosion depth. The primer or booster charge has in some instances been made movable, being primarily out of reach of the cartridge, so that the explosion of the latter will not explode the primer charge; and being connected to the primary hydrostat, so that the bomb in descending to the preliminary set depth (say 20 feet) will lift the primer charge within reach of the cartridge, after which the further descent of the bomb to the final set depth (say, for example, 50 feet) will cause the explosion of the cartridge and thereupon the consequent explosions of the primer or intermediate charge and the main charge.

The present invention aims to improve upon the construction of such depth bombs and to simplify them and make their safety provisions more reliable.

According to the present invention the intermediate charge is preferably fixed in place within the main charge. The primary hydrostat operates a sliding member which normally cuts off communication between the chamber containing the cartridge

and the intermediate charge. The descent of the bomb to the preliminary set depth (say 20 feet) moves this part so as to establish such communication. It also admits hydrostatic pressure to the secondary hydrostat, the subsequent movement of which to the final set depth (say 50 or 60 feet) determines the explosion.

The general nature of the invention being thus understood, its preferred embodiment will now be described with reference to the accompanying drawings, wherein,—

Figure 1 is a longitudinal mid-section through the mine or bomb, showing it in the loaded position ready for launching.

Fig. 2 is a fragmentary transverse section on the line 2—2 in Fig. 1, the cartridge being removed.

Fig. 3 is a section similar to Fig. 1, but showing the parts after the preliminary set depth has been reached and while the subsequent movement toward the final depth is in progress.

Fig. 4 is a fragmentary transverse section on the line 4—4 in Fig. 3.

Fig. 5 is a fragmentary view on a larger scale, showing the condition immediately after the release of the hammer which causes the explosion.

Fig. 6 is a fragment corresponding to the lower part of Fig. 1, showing the condition of the parts in case of the premature explosion of the cartridge before launching the bomb.

Fig. 7 is an elevation of the bomb on a reduced scale.

It will be understood that Figs. 1 and 3 show only those portions of the bomb to which the present invention relates, the portion broken away being continued in practice to any desired dimensions, according to the size of bomb and charge of high explosive that may be required.

The bomb is formed, as usual, with an outer shell or casing A of sheet-metal. This shell is shown hemi-spherical at one end, but this is not essential. The major portion of the capacity within the shell is taken up by a charge B of high explosive (usually TNT). Within a central chamber or cavity is located, as usual, the intermediate explosive charge C, commonly called the primer or booster charge. The primary explosive D in the form of a cartridge may be variously arranged, so that when exploded it will in turn explode the intermediate charge.

The bomb has two hydrostats, the primary hydrostat being indicated as a whole by the letter E, and the secondary hydrostat by the letter F. Each hydrostat consists of 5 a diaphragm or piston subjected to water pressure and opposed in its movement by a spring. The primary hydrostat at first is the only one receiving the water pressure; its movement to the primary set depth in 10 turn admits water to act upon the secondary hydrostat, whereupon the latter moves proportionally to the further increase in hydrostatic pressure.

The primary hydrostat E is shown as 15 including a cylindrical corrugated diaphragm *a* (which may well be constructed of the type known as the sylphon), and which is opposed by the stress of a spring *b*. The diaphragm *a* is enclosed in a chamber *G* which is conveniently formed in a transverse tubular casing *H*, as shown. The diaphragm *a* is shown as attached to a cap *c* closing one end of the casing *H*, this attachment being through the medium of a 20 disk or end piece *d* to which one end of the diaphragm is immediately connected, its other end being united to a disk *e* which is detachably connected to the main safety slide *J*. This slide *J* is conveniently made 25 of cylindrical form and slides freely through a cylindrical neck or guide-way *f* formed in the intermediate portion of the casing *H*. The opposite end portion of this casing is expanded to form a chamber *K* which encloses 30 the spring *b*. Between the portions *f* and *K* the casing *H* is formed with a cylinder *g* in which is movable a piston *i* preferably formed integral with the slide *J*. The chamber *K* is closed by a disk *j* screwed 35 into the casing *H* and against which the spring *b* reacts, and which is perforated at *h* to admit water into this chamber. The water thus admitted cannot pass the piston *i* when the parts are in the normal position 40 shown in Fig. 1. The safety slide *J* has a solid portion *m* which in the normal position closes a firing hole *p* which communicates with a cartridge-receiving chamber *q* formed within the intermediate charge *C*. 45 The safety slide has an opening *r* which, as the primary hydrostat yields to the hydrostatic pressure, moves downward, and upon reaching the primary set depth enters into coincidence with the opening *p*, this being 50 the position shown in Fig. 3. To keep the slide *J*, if formed cylindrically, from turning within the shell *H*, it is provided at its upper portion in Fig. 1 with a groove *o* engaged by a key or lug *s* on a disk *s'*, as 55 shown in Figs. 1 and 4, these parts having a free sliding fit.

The secondary hydrostat F is shown as including a piston *L* which slides, against the stress of a spring *S*, in a cylinder *M* arranged at right angles to the casing *H*,

and preferably in the longitudinal axis of the shell *A*. At its inner end this piston is closed by a freely removable disk *t* which normally carries a frangible thin metal disk *t'* (Fig. 2) having a central hole for guiding the cartridge *D*. As the piston *L* moves forward the cartridge slides in this hole. 70

The piston *L* carries a tubular shell *N* within which is mounted the hammer *P* formed with a projecting firing pin *P'*, and 75 receiving behind it the pressure of a suitably stiff spring *Q*. When set ready for firing, the hammer is held by sears *R* (one or more), each having a projecting tail *R'* which, as the parts move to the final depth, 80 encounters the disk *t* (see Fig. 3), and by the final movement is swung backwardly (see Fig. 5), thereby releasing the hammer, so that the latter is projected forward to cause its pin to enter the cap or fulminate 85 charge of the cartridge and explode the latter. The cartridge might be stationary, but is preferably mounted on the end of the tubular shell *N* by means of a screw cap *u* (Fig. 5) or in any other suitable manner. 90

The slide *J* is cut away on one side to form a chamber *v* of sufficient size to avoid the slide touching the cartridge, and sufficiently large to admit the end of the shell *N* when the latter is projected. Extending from this 95 chamber to the lower end of the slide *J*, the slide is formed with a tubular passage *w* which at the outer end is closed by any suitable part *x*, preferably a thin metal disk, so mounted as to be easily blown out in 100 case of a premature explosion of the cartridge *D*. Thus, if with the parts in the position shown in Fig. 1 anything should happen by which the cartridge should be exploded, this explosion would not explode the bomb 105 because the solid portion *m* of the slide would prevent the burning powder or hot gases entering through the firing hole *p*, and these would simply blow out harmlessly through the passage *w* and thereby blow off 110 the disk *x*. This disk *x* thus serves as an indicator. If in place, it shows that the cartridge is intact; if blown out, as shown in Fig. 6 (which is apparent at a glance) it indicates at once to the operator that the 115 cartridge has been prematurely blown and the bomb is unworkable.

The operation is as follows:

The bomb will have been initially charged with the usual explosive charges *B* and *C*. 120 In preparing it for use the operator will remove the cap *M'* which closes the end of the cylinder *M*, and will take out the piston *L* with its attached parts. He will also see that a disk *t* with an intact frangible portion *t'* is in place at the bottom of the cylinder *M*. He will then set the hammer *P* against the stress of its spring and see that it is properly held by the sears *R*. He will then apply the cartridge *D* which is attached 125 to the piston *L*. The operator will then 130

to the cap α , by screwing this cap onto the end of the shell N . He will then insert the piston L into the cylinder, thereby thrusting the parts which it carries forward and 5 introducing the end of the cartridge into the guiding neck of the inner disk t to the position shown in Fig. 1. In so doing he compresses the spring S slightly to its initial tension, this being accomplished in the act 10 of screwing in the cap M' , whereby the cylinder M is closed. It is assumed that the slide J and its appurtenant parts (none of which need ever be removed) were previously in proper position, and that if the end 15 disk α had at any time been blown out, a new one is supplied. The bomb thus is in readiness for launching, all the parts being in the position shown in Fig. 1.

The bomb in this condition may be handled with perfect safety, there being no possibility of any explosion occurring. Even if the hammer were to become released from its sears (which could not happen if properly loaded) it could only explode the cartridge, which would harmlessly blow out the cap α , doing no further damage, in which case the absence of this cap would betray to the operator that the bomb had become useless.

Upon launching, the bomb is dropped overboard and descends in the water by its weight. The hydrostatic pressure can affect only the primary hydrostat E by entering its diaphragm, and as this pressure increases 35 the slide J will gradually move down against the stress of the spring b , until at or near the primary set depth the piston i passes out of the cylinder g , as shown in Fig. 3, and thereby permits water to enter under pressure through the openings k , chamber K , cylinder g , and through passage T to the interior of the cylinder M , where it acts 40 upon the piston L of the secondary hydrostat F and advances this piston against the stress of its spring S . This advance is gradual as the bomb descends; during this advance the cartridge D enters through the firing hole p into the recess q in the intermediate explosive charge C , as shown in Fig. 50. Finally when the set depth is reached, the sears R are released in the manner described and the hammer flies forward, its pin striking the cap and exploding the cartridge. As the cartridge thus explodes with 55 in the charge C , the latter is exploded with great certainty, and this in turn explodes the main charge B .

The slide J is of such length that in its initial position shown in Fig. 1 its lower 60 end comes just within the exterior dimensions of the shell of the bomb. If wrongly assembled (for example, if the spring b were omitted) the slide would in the handling of the bomb become displaced, which would 65 at once be betrayed by its end projecting be-

yond the shell of the bomb, as shown in Fig. 3. Thus, the operator would be warned to examine the parts before attempting to launch the bomb.

In order to avoid any counter-pressure 70 which might materially affect the operation of the hydrostats, provision is made for venting the chambers from the side opposite to that which receives hydrostatic pressure into a somewhat large chamber U which is 75 formed in the end portion of the shell or casing A by means of a partition y which divides the interior of the casing, the portion to the right of this partition in Fig. 1 being filled with the explosive charge. The vent 80 to the chamber U from the diaphragm chamber G may be effected by a short tube y' , while the vent from the interior of the cylinder M into the chamber U may be effected by means of a port or opening z . Before 85 launching, the chamber U is filled with air at atmospheric pressure; as the bomb descends, the movement of the hydrostats displaces some fluid into this chamber, but not enough to create any material back-pressure 90 therein such as would impair the action of the hydrostats.

If desired, the chamber G may be filled with heavy oil or grease for lubricating the diaphragm α and its appurtenant parts, and also for lubricating the slide J in its movements within the tubular shell H . As the diaphragm α expands, some of this grease will be expelled through passage y' into the chamber U , but without any detrimental effect.

It will be understood that the use of the intermediate explosive charge C as a primer, while practically desirable, is not essential to the present invention.

The safety slide J may be easily removed by unscrewing the cap j . By removing the cap c the primary diaphragm α with its cap e may be taken out, the neck of this cap having a free sliding fit with the slide J . The slide J may then be pushed down and out and freely withdrawn. The cartridge D should either be absent or its length should be insufficient to cause it to project into the path of the slide.

To cause the piston i to make a water-tight joint in the normal position, it is desirable to fit it with a gasket i' .

For effecting a joint between the passage T and the tubular shell H , it is desirable to interpose a bushing j' , as shown, so that the parts may be united by a sliding joint.

I have shown no adjustments for the hydrostat springs b and S , because the provision of such adjustments would be a needless complication. It is preferable to construct these springs of the desired resiliency to cause the hydrostats to accomplish their movements at certain predetermined depths respectively. If it is desired that either hy-

drostat be caused to act at a different set depth, this can be accomplished by having in reserve one or more additional springs having different resiliency or stress, and these may be substituted for either of the springs δ or S to accomplish the desired change in the respective operating depths.

It is one of the advantages of the improved bomb provided by this invention that it is adapted for safe discharge from a launching tube such as is used for launching automobile torpedoes. By making it of the proper diameter to fit such tubes and of a suitable length (being approximately the proportions shown in Fig. 7) it may be ejected from such a launching tube in exactly the same manner as a torpedo. For such use it has the special advantage incident to the transverse movement of the safety slide J , that if any derangement occurs which causes the protrusion of this slide, as shown in Fig. 3, it cannot be entered into the launching tube; it also has the advantage that while the absence of the disk α would betray the fact of premature explosion of the detonator, the presence of this disk, which in connection with the normal position of the slide J affords assurance of the correct operative condition of the bomb, guards against any introduction of compressed air from the launching tube such as might leak past the sides of the bomb and enter through the passage w , and which, if it were to enter within the cylinder M , might derange the hydrostatic action of the secondary hydrostat F . The disk α affords maximum resistance against inward pressure, while affording only sufficient resistance against outward pressure to hold it in place under normal conditions.

It will be understood that while the embodiment of the invention here illustrated and described is the preferable one, yet the details of construction may be considerably varied according to practices well understood in this art, and that such structural variations may be made without departing from the present invention, within the scope of the appended claims.

In the claims the cartridge or its equivalent is referred to as a detonator, and the explosive charge includes both the intermediate charge C and the main high explosive B , if both are used.

What I claim is:—

1. A depth bomb having an explosive charge and a detonator, with primary and secondary hydrostats, safety means normally interposed to prevent exploding said charge from the detonator and adapted to permit such explosion on responding to a preliminary set depth, and said secondary hydrostat adapted to explode the detonator upon reaching a final set depth.

2. A depth bomb according to claim 1, said safety means including a movable part

which uncovers a firing hole on responding to the preliminary set depth.

3. A depth bomb according to claim 1, said exploding charge having an internal cavity communicating with a firing hole, and said safety means including a movable part which uncovers said firing hole on responding to the preliminary set depth.

4. A depth bomb according to claim 1, said exploding charge having an internal cavity communicating with a firing hole, and the secondary hydrostat carrying the detonator and adapted on approaching the final set depth to project the detonator through said firing hole into said cavity.

5. A depth bomb having an explosive charge, a detonator, and primary and secondary hydrostats, with a fluid passage for admitting hydrostatic pressure to the secondary hydrostat, and means controlling said passage adapted upon the movement of the primary hydrostat responding to a predetermined depth to open said passage.

6. A depth bomb having an explosive charge and a detonator, with primary and secondary hydrostats, with safety means operated by the primary hydrostat and means for exploding the detonator operated by the secondary hydrostat, and means controlled by the primary hydrostat for admitting hydrostatic pressure at a predetermined depth to the secondary hydrostat.

7. In a depth bomb having an explosive charge and means for exploding it, a hydrostatically-operated safety device comprising a movable slide primarily occupying a safety position where it is interposed to prevent the action of said exploding means, and a hydrostat adapted at a predetermined depth to displace said slide into position to permit the operation of said means and thereby cause the explosion of the contained charge.

8. A depth bomb having an explosive charge formed with an internal cavity communicating with a firing hole, and a safety device comprising a hydrostatically-operated movable part adapted at a predetermined depth to uncover such firing hole, and means adapted thereafter to introduce a detonator through said hole into said cavity.

9. A depth bomb having an explosive charge and a detonator, with a safety means normally interposed to prevent explosion of the detonator from exploding said charge, and a vent adapted to discharge externally the products of such explosion of the detonator in such safety position.

10. A depth bomb comprising a safety device interposed between a detonator and explosive charge, said safety device formed as a slide movable under hydrostatic control and having a vent passage for discharging externally any products resulting from a premature explosion of the detonator.

11. A depth bomb according to claim 9, having a fragile closure for said vent passage adapted to be blown off in the event of a premature explosion to thereby indicate its occurrence.
12. In a depth bomb having an explosive charge and means for exploding it, a safety device and a hydrostat operating it, said safety device in its normal safety position located within the bomb and adapted upon moving to firing position to project beyond the bomb.
13. A depth bomb comprising primary and secondary hydrostats, a safety device operated by the primary hydrostat and consisting of a slide carrying a valve, and a passage from the exterior to the secondary hydrostat controlled by such valve, such passage being normally closed, but opened under control of the primary hydrostat at a preliminary set depth.
14. A depth bomb having primary and secondary hydrostats, and an empty chamber communicating with the chambers of said hydrostats into which fluid may be expelled from said chambers as the hydrostats respond to hydrostatic pressure.
15. A depth bomb having primary and secondary hydrostats, and a safety device controlled by the primary hydrostat, a transverse shell in which such safety device moves, and a longitudinal cylinder enclosing the secondary hydrostat, with removable means for giving access to said hydrostats from the exterior.
- In witness whereof, I have hereunto signed my name.

WILLIAM DIETER.
